UNITED STATES PATENT OFFICE.

DAVID B. OLIVER, OF ALLEGHENY, PENNSYLVANIA.

ROLL.

SPECIFICATION forming part of Letters Patent No. 397,563, dated February 12, 1889.

Application filed April 26, 1888. Serial No. 271,969. (No model.)

To all whom it may concern:

Be it known that I, DAVID B. OLIVER, of Allegheny, in the county of Allegheny and State of Pennsylvania, have invented a new 5 and useful Improvement in Rolls; and I do hereby declare the following to be a full, clear, and exact description thereof, reference being had to the accompanying drawings, in which—

10 Figure 1 is a front view of my improved rolls removed from the housings. Fig. 2 is an end view of the rolls and their housings. Fig. 3 is a top plan view of the housings. Fig. 4 is a side view of the top of the housings.

15 Like symbols of reference indicate like parts in each.

In rolling skelp-iron slabs for covers for plate-iron piles and similar material it has been usual to employ grooved two-high rolls, 20 the top roll of which is balanced, and is provided with adjusting-screws by which it is vertically movable in the housings. The metal is passed between the rolls, and after setting down the top roll the metal is passed 25 back by heave-up hooks over the top roll, and successive passes or reductions in a single direction are given to it until it is reduced to the desired thickness. The partings between the tongue of the top roll and the groove of 30 the bottom roll cause a fin or flash on the piece, which makes it necessary, for the purpose of effacing the fin, to turn the piece over at each pass, so that the top of the slab shall be at the bottom of the groove at the next 35 pass. Passing the iron back over the rolls and reversing it at each pass are laborious operations, requiring the presence of additional men at the rolls, and therefore increasing the cost of production.

40 As distinguished from the prior state of the art as thus set forth, my invention consists in a three-high set of tongued and grooved rolls—such as are shown in Fig. 1 of the drawings—which are adjustable to vary the sizes of the 45 passes, of which one of the rolls is fixed, and the other two are suitably balanced, and the top roll is movable vertically by means of adjusting-screws. In the use of these rolls the iron is first passed between the bottom and 50 middle rolls, then raised by a suitable feed-table and passed back between the top and middle rolls, and so on until the desired re-

duction is obtained, the rolls at each pass being adjusted to diminish the size of the opening between them. By this method of rolling 55 it is not necessary to turn the metal slab to reduce the fin, because the side of the slab which is next the middle roll and on which the fin is formed at one pass is at the next pass at the base of the groove and farthest 60 from the middle roll. These rolls are of great utility, not only because they obviate the necessity for passing the metal back over the rolls at each pass, as in the two - high rolls, but also because they prevent the formation 65 of fins on the metal without need of reversing it at each pass, and because with a set of three-high rolls having a single pass above and below I am enabled to do the same work as with a set of non-adjustable rolls of much 70 greater length and having a number of passes or grooves.

In rolling slabs or plates of considerable width the labor of turning the metal over at each pass is so great as to render the use of 75 two-high rolls difficult and expensive, if not impracticable. With the use of three-high tongued and grooved adjustable rolls I am enabled to roll metal of great width and weight, which, by reason of the confinement of 80 the metal in the grooves, is compact and even at the edges. A vertically-lifting feed-table with driven feed-rollers may be conveniently used in connection with the rolls.

As compared with the use of plain rolls, the 85 iron is produced more cheaply, because the edges are regular and do not have to be trimmed off.

Rolls constructed on this principle may be arranged in a variety of ways—for example, 90 the bearings of the middle roll may be fixed, the top and bottom rolls being adjustable to and from it; or the bearings of the top roll may be fixed; the middle and bottom rolls being adjustable, or the bearings of the bottom 95 roll may be fixed and the top and middle rolls adjustable. I have shown the last-named arrangement in the drawings, in which 2, 3, and 4 are the top, middle, and bottom rolls, respectively, the top and bottom rolls 100 being grooved, and the middle roll having a tongue which fits within these grooves. The bearings of the bottom roll, 4, are stationary, and the bearings of the middle roll are

mounted on a yoke, 24, which connects the upright rods 5 with the pistons of hydraulic cylinders 6, a pump, 25, being provided for furnishing water, which acts on the under sides of the pistons and tends to raise the bearings of the roll. When the slab is to be passed between the middle and bottom rolls, the hydraulic pistons are raised so as to elevate the middle roll against the journals of the top roll, and when the slab is to be passed between the top and middle rolls the water is allowed to escape, and the middle roll then falls by gravity until its journals rest on the journals of the bottom roll. With this arrangement it is only necessary that the top roll should be provided with adjusting-screws. These are shown clearly in the drawings. 11 and 12 are adjusting-screws arranged vertically in the housings at each end of the rolls and resting at their lower ends on the bearings of the top roll. These screws are turned by means of pinions 13, keyed thereto, and connected by an intermediate gear-wheel, 14, which is fitted with a feather and spline on a rotary vertical shaft, 15. The shaft 15 is driven by a gear-wheel, 16, which is fixed thereto, and which meshes with a pinion, 17, on a vertical shaft, 18. This shaft 18 is driven from a primary driving-shaft, 19, by means of intermeshing beveled pinions 20. The screws are connected by a yoke, 22, which encircles them, and which is supported by collars 23. When thus arranged, it is obvious that the rotation of the primary shaft will drive the screws, and will thus raise or lower the bearings of the top roll accordingly as the shaft is driven in one direction or the other, the force to raise the roll being supplied by a suitable counter-balance.

When the rolls are in operation, at each pass of the metal between them the adjusting-screws are turned so as to depress the bearings of the top roll and to lessen the distance between the top and bottom rolls and to effect a corresponding reduction of the metal.

By the use of the term "adjustable rolls" in this specification I mean three-high rolls, which are in practice adjusted throughout the operation of rolling, so that the metal rolled can be reduced in thickness at each successive pass in the same grooves.

The rolls may be very greatly modified in the construction and arrangement of the parts by which they are adjusted in the housings, 55 since I do not limit myself to the specific form which I have shown and described.

I am aware that a three-high mill having plain rolls has heretofore been provided with guide-collars and grooves at the ends to prevent lateral play of the rolls, and do not claim the same; but

What I claim is—

1. In a three-high mill, the combination of the housings, a roll set in stationary bearings 65 in the housings, two rolls set in vertically-movable bearings therein, a lifter acting on one of the vertically-movable rolls to raise the same in the housings, and adjusting-screws connected with the bearings of the other of said 70 movable rolls, said rolls being tongued and grooved to form working and reducing passes, having the tongues oppositely placed in the reverse passes, whereby the plate or slab to be rolled is continuously reduced, and the 75 flash or fin formed at one pass is effaced at the reverse pass without reversing such plate or slab, substantially as and for the purposes described.

2. In a three-high mill, the combination of 80 the housings, a roll set in stationary bearings in the housings, two rolls set in vertically-movable bearings therein, hydraulic cylinders, the piston-rods of which act on the bearings of one of the vertically-movable rolls to 85 raise the same in the housings, and adjusting-screws connected with the bearings of the other of said movable rolls, said rolls being tongued and grooved to form working and reducing passes, having the tongues oppositely 90 placed in the reverse passes, whereby the plate or slab to be rolled is continuously reduced, and the flash or fin formed at one pass is effaced at the reverse pass without reversing such plate or slab, substantially as and 95 for the purposes described.

In testimony whereof I have hereunto set my hand this 5th day of April, A. D. 1888.

DAVID B. OLIVER.
